J. H. GOSSETT.
AUTOMATIC LOOM STARTER.
APPLICATION FILED MAR. 15, 1920.

Patented Feb. 22, 1921.

2 SHEETS—SHEET 1.

A black and white photograph of a business card. The card features a drawing of a pipe fitting in the upper left corner. To the right of the drawing, the name 'J.H. Gassett' is written in a cursive script, with 'INVENTOR' printed in a smaller, sans-serif font below it. Below this section, the word 'BY' is printed in a small, sans-serif font. To the right of 'BY', there is a large, stylized signature that reads 'Victor J. Morris'. In the bottom right corner of the card, the word 'ATTORNEY' is printed in a sans-serif font.

UNITED STATES PATENT OFFICE.

JAMES H. GOSSETT, OF ANDERSON, SOUTH CAROLINA.

AUTOMATIC LOOM-STARTER.

1,369,651.

Specification of Letters Patent. Patented Feb. 22, 1921.

Application filed March 15, 1920. Serial No. 365,933.

To all whom it may concern:

Be it known that I, JAMES H. GOSSETT, a citizen of the United States, residing at Anderson, in the county of Anderson and 5 State of South Carolina, have invented new and useful Improvements in Automatic Loom-Starters, of which the following is a specification.

The object of the invention is to provide 10 a simple and effective means for starting one or a plurality of looms and similar machines from a central station under such conditions that the starting operation may be under the personal control of a superintendent or foreman to avoid dependence upon individual loom attendants or operators and to insure the starting of all of the looms which are to be operated at a given predetermined time with a view to systematizing 15 the work and controlling to that extent the activities of the employees and with this object in view the invention consists in a construction, combination and relation of parts of which a preferred embodiment is shown 20 in the accompanying drawings, wherein:—

Figure 1 is an elevation of the starting mechanism applied in the operative position to a loom shipper.

Fig. 2 is a sectional plan view on the plane 30 indicated by the line 2—2 of Fig. 1.

Fig. 3 is an enlarged view of the cylinder and its associated parts showing the piston in dotted lines.

The device consists essentially of a cylinder 35 having a base plate or bracket 11 adapted to be attached to a loom side indicated at 12, a piston 13 being mounted in said cylinder and having its rod 14 provided with a tappet block 15 for engagement with a collar 16 which is slidably fitted upon said rod in the path of the tappet. Said collar is connected by a stem 17 with a sleeve 18 fitted upon the shipper lever 19 mounted in the usual way on a bracket 20 and having its upper free end provided 45 with a shipper handle 21 operating in connection with a slotted guide 22 and adapted to be locked in the active or loom starting position shown in Fig. 1. The shipper arm 50 or lever as in the ordinary practice is yieldingly held in its neutral or loom stopping position by means of a coiled spring 23 which is adapted to return said lever to its

loom stopping position in the event that it should be released, or any disarrangement of 55 the loom structure or element should occur.

Communicating with the cylinder 10 is an air supply pipe 24 provided adjacent to each loom with a cut-off valve 25, so that any loom may be cut out of a system of starting 60 mechanism including a plurality of machines, said air supply pipe being in communication with a main supply line adapted to be controlled at a central station as from 65 the office of the factory.

It will be understood that previous to the starting hour the valve 25 of such looms as are not to be used being closed, the opening of the controlling valve to admit pressure to the main air supply line at the hour of starting will result in a distribution of pressure 70 to the several looms which are to be used and such pressure acting upon the several pistons 13 will advance the latter and through the action of the tappet blocks 15 coming 75 into contact with the collar 16, the shipper levers of all of the looms will be thrown to the loom starting position. The pressure in the supply pipes may then be relieved to permit of the return of the pistons to their 80 normal or neutral positions to the end that in the event of the release of the shipper lever of a loom it will be free to return to its neutral position to stop the operation of 85 that particular loom.

Having described the invention what is claimed is:

1. An automatic loom starter having a cylinder and means for supplying pressure thereto, a piston operating in said cylinder 90 and having its rod provided with a tappet block, and a collar slidably mounted upon the piston rod in the path of said tappet block and operatively connected with the shipper of the loom. 95

2. An automatic loom starter having a cylinder and means for communicating pressure thereto, a piston operating in said cylinder and having its rod provided with a tappet block, a collar slidably mounted 100 upon the piston rod in the path of said tappet block, a sleeve attachable to a shipper lever, and a stem connecting said sleeve and collar for the communication of motion from the latter to the former. 105

3. An automatic loom starting mecha-

nism having a cylinder provided with means for attachment to a loom side adjacent to the shipper lever, a valved air supply pipe in communication with said cylinder, a piston 5 ton operating in the cylinder and having its rod provided with a tappet block, a collar slidingly mounted upon the piston

rod in the path of said tappet block, and connections between the collar and the shipper for communicating motion in one direction thereto. 10

In testimony whereof I affix my signature.

JAMES H. GOSSETT.
